RANGE FINDER

Stephen M. MacNeille and Joseph Mihalyi, Rochester, N. Y., assignors to Eastman Kodak Company, Rochester, N. Y., a corporation of New Jersey

Application June 23, 1943, Serial No. 491,955

15 Claims. (Cl. 88—2.7)

1
This invention relates to range finders. This is Case N of a series of applications relating to the same subject and including the following:

Title	Serial No.	Filed	Inventors
Mount for optical element.	461,584	Oct. 10, 1942	Mihalyi.
Range finder construction.	461,585	Oct. 10, 1942	Do.
Range finders—Case A.	472,831	Jan. 19, 1943	Do.
Range finders—Case B.	472,832	Jan. 19, 1943	Do.
Range finders—Case C.	472,833	Jan. 19, 1943	Do.
Range finders—Case D.	472,834	Jan. 19, 1943	Mihalyi, MacNeille.
Range finders—Case E.	472,835	Jan. 19, 1943	Mihalyi, Tuttle.
Range finders—Case F.	479,096	Mar. 13, 1943	Mihalyi.
Range finders—Case G.	479,097	Mar. 13, 1943	Do.
Range finders—Case H.	479,098	Mar. 13, 1943	Holmes, Mihalyi.
Range finders—Case I.	479,099	Mar. 13, 1943	Mihalyi, MacNeille.

Range finders—Case P.	526,020	Mar. 11, 1944	Do.
Range finders—Case T.	508,186	Oct. 29, 1943	Do.

The purpose of the present case is in general similar to that of Case M, namely, to give double sensitivity in the collimating system of an autocollimating or range correction setting type of range finder. However, the present case employs an entirely different method.

It is an object of a preferred embodiment of the invention to allow the range correction setting elements to be viewed by the main observer. In one embodiment the double sensitivity feature is incorporated into prior range correction setting systems such as described in certain of the above listed cases of this series, without altering the main part of the optical system in any way. The invention is also useful with other forms of adjustment coincident elements as will be pointed out but is far more useful with range correction setting systems than with the others.

As mentioned in Case M, autocollimating systems including range correction systems depend for their advantages on the fact that the additional optical elements of the collimator system as distinguished from the main range finder optical system, can be made quite small and hence, more stable in their adjustment. However, when the shift of the adjustment coincident element image is of the same magnitude as the shift of the main target image due to any maladjustment, the collimator image, i. e. the image of the adjustment coincident element, must be read with the same high order of care as is used in reading the coincidence or stereo depth of the object images. Any system which doubles the sensi-

2
tivity of the collimator control gives an ultimate range reading which is for all practical purposes dependent only on the reliability of the main range reading.

According to the present invention, this increased collimator sensitivity, usually double sensitivity, is obtained by having the collimator beam from one adjustment coincident element in one of the comparison planes of the range finder travel around the range finder optical system and from one viewing point to the other, as described in detail in many of the above-listed cases, and particularly by having at the receiving end of this element light beam, opposed reflector means for giving relative movement of two parts of the element image, which relative movement is at least twice the movement of either part alone. As applied to pure autocollimation, this invention requires the adjustment coincident element to consist of both a scale and an index which are affected oppositely, that is, so that the image of the index moves along the image of the scale as the range finder is adjusted. The double sensitivity feature permits a larger, more easily read scale to be used.

The most useful embodiment of the present invention is in pure range correction setting as primarily described in Case I of this series. The opposed reflector means is preferably a dihedral reflector with its roof edge in the comparison plane near which the element images are formed. When the terms horizontal and vertical are used merely relative to one another and in an optical sense as in all of these range finder cases, the roof edge of the dihedral reflector should be vertically oriented. The exact orientation of the rest of the reflector is not critical, but one preferred embodiment of the invention employs a porro prism with its hypotenuse face facing the 40 incident light.

If the range correction setting mark is but a single one, the resulting pair of images in any of the forms produced by a dihedral reflector are spaced from each other only when the instrument involves some maladjustment and are in coincidence when the instrument is in proper adjustment. However, the coincidence requires, in this case, that the images be formed exactly at the roof edge of the dihedral reflector. Even if it were possible to make a perfect roof edge, it would not be convenient to use such arrangement. Hence, in highly accurate systems, we prefer to use an adjustment coincident element consisting of two vertical lines or marks, which may be either dark or bright, and which are

horizontally spaced on one of the comparison planes. The element light beam from this double element, which incidentally is preferably produced optically from a single mark or line and consists of the mark and a virtual image thereof or two such virtual images, is projected through the usual collimator optical system and the two parts of the beam impinge on opposite faces of the dihedral reflector. The dihedral reflector has its roof edge at the point conjugate to one midway between the two lines which constitute the adjustment coincident element. When the range finder is in proper adjustment, the two element images are equally spaced from the roof edge of the dihedral reflector, and hence will appear in coincidence either when the two beams are reflected toward each other, or if one of these reflecting surfaces is semi-transparent or intercepts only part of the element beam and an additional reflector is included, when the two beams are reflected sideways in the same direction. However, any shift due to maladjustment of the range finder causes one part of the element light beam to move toward the roof edge and the other to move away from it so that the images move apart with twice the rapidity of the motion of either of them.

In one particularly preferred embodiment of the invention an additional reflector is included for directing these two beams toward the eye of the main observer. Also, an additional lens or an additional optical path of glass is preferably included to insure that the element images appear to the observer to be in the same plane as the target images so that a single adjustment of the eyepiece of the instrument will serve for both observations. The dihedral reflector and the additional reflector may be formed of two very small prisms which can be mounted in the focal plane of the eyepiece of a range finder, usually without interfering in any way with the main optical system.

The advantages of the invention will be fully understood from the following description when read in connection with the accompanying drawings, in which:

Fig. 1 shows a stereo range finder incorporating a simple form of the invention, Fig. 1A being the binocular field of view through the instrument;

Figs. 2, 2A and 2B illustrate in magnified form one detail of Fig. 1;

Fig. 3 shows a similar form of the invention intended for pure autocollimation, Fig. 3A being an enlarged view of one detail of Fig. 3 and Fig. 3B showing the field of view of the scale reading observer;

Fig. 4 shows a preferred embodiment of the invention applied to coincidence range finders, Fig. 4A being the field of view of the observer;

Figs. 5 and 5A show an enlarged detail of Fig. 4;

Fig. 6 shows an alternative form of the detail shown in Fig. 5;

Figs. 7 and 7A show still another alternative for this detail;

Fig. 8 shows another detail of Fig. 4 greatly enlarged and in perspective;

Fig. 9 shows a preferred alternative of the detail shown in Fig. 8;

Figs. 10 and 11 show alternative arrangements for a portion of the instrument shown in Fig. 1, Fig. 10A being the field of view of the auxiliary observer;

Figs. 12 and 13 show portions of a range finder alternative to those shown in Fig. 4;

Fig. 14 shows still another alternative for the detail shown in Fig. 13;

Figs. 15 to 18 illustrate one form of beam splitter for producing a pair of lines to be used as an adjustment coincident element;

Fig. 19 illustrates a pair of prisms equivalent to the mirror system of Figs. 15 to 18;

Fig. 20 shows a slightly different embodiment of this beam splitter, which is also useful as the receiving dihedral reflector system;

Fig. 21 shows an arrangement alternative to that of Fig. 20;

Figs. 22 and 22A illustrate a simplified form of dihedral reflector according to the invention;

Figs. 23 and 23A illustrate the operation of such a dihedral reflector when a single line adjustment coincident element is used;

Fig. 24 illustrates why the invention is not sensitive to rotation of the dihedral reflector.

In Figs. 1, 1A, 2, 2A and 2B light from a distant object represented by two small aeroplanes 30 is received at the viewing points of a stereo range finder by optical squares 31 and directed through objectives 32 into focus in comparison planes on the surface of field lenses 33 and 34. The object images are viewed stereoscopically by reflectors 35, relay lenses 36, rhombs 37 and eyepieces 38. The apparent object distance is adjusted by a light deviator 40 operating on one of the object beams. According to the invention, light from a lamp 43, as reflected by prism 44 illuminates an adjustment coincident element consisting of two horizontally spaced vertical marks 45. In this particular embodiment, the vertical marks 35 are complementary, one continuing where the other leaves off as shown in Fig. 1A. Light from this pair of lines is collimated by the right hand objective 32 and is directed from one viewing point to the other by a small penta prism 46, and thence by another penta prism 47, back into the range finder system to be brought to focus near the other comparison plane 33. At this other comparison plane, a porro prism 48 is positioned with one of its roof surfaces 49 fully reflecting and the other 50 semi-transparent and with its roof edge vertically oriented and in the comparison plane. Behind the semi-transparent roof surface 50 is a plane reflector 51. The two parts of the element light beam are received respectively on the surfaces 49 and 50. One of these is transmitted through the surface 50 and after reflection at the reflector 51 back through the surface 50 and the other is reflected first by the surface 49 and then by the surface 50 so that both of them are directed back toward a semi-transparent reflector 52 so that the images may be viewed through an eyepiece 53 by the eye 54 of an auxiliary observer. When the instrument is slightly out of adjustment as indicated by the position of the element rays in Fig. 2A, this auxiliary observer 54 sees a field of view as shown in Fig. 2B in which the element images 45' are not in coincidence. By means of a zero adjustor 55, the maladjustment of the instrument is corrected so that the two element images as they strike the surfaces 49 and 50 are equi-distant from the roof edge of the porro prism 48, at which time the line images 45' will be in coincidence and appear as a single line. The auxiliary observer 54 by operating the zero adjustor 55 maintains proper calibration of the instrument at all times and the main observer is left to judge the apparent distance of the object images 30' and to vary this apparent distance by the light deviator 75.

40 until it matches some standard reticle, in the usual manner.

Fig. 3 differs from Fig. 1 by the use of an adjustment coincident element which consists of a scale 62 and an index 63. A large prism 61 is used to illuminate this element. Light from the element passes through the same system as before so that the observer 54 sees a scale image 62' and an index image 63' which gives the range directly. In this case, a light deviator 60 is included in one of the object beams and in the element beam rather than separate therefrom, so that autocollimation is secured. The double sensitivity feature produced by the opposed reflectors consisting of the roof surfaces of the prism 48, 15 in this case merely permits a larger scale to be used.

In Fig. 4 a coincidence type range finder is shown in which light from the object being ranged is received on optical squares 65 and directed through objectives 66 to crossed reflectors 67 and 68 and thence into focus in superposition in an image field 69, which consists of coplanar comparison planes. The object images are viewed through an eyepiece 70 by the eye 71 of an observer. According to the invention as shown in Figs. 4 and 8, light from a lamp 72 reflected by a prism 73 illuminates a single vertical mark 73 which may be either bright or dark. This mark is optically split into two parts by a rhomb 74 so that the light 75 from one part thereof is horizontally displaced from the other. This light is reflected by the prism 68, collimated by the objective 66 and reflected from one viewing point to the other and back into the optical system by two small prisms 75 and 76 which differ from pure optical squares just sufficiently to compensate for the fact that mark and prism system 73, 74, 78 is not in the center of the field 69. The separation of the two parts of the mark causes the light beams therefrom to cross symmetrically between the viewing points. These light beams after reflection by the prism 67 are received on opposite roof surfaces 82 and 83 of a porro prism 77 positioned with its roof edge vertical in the comparison plane 69 at the point conjugate to one midway between the two lines formed by the beam splitter 74. When the instrument is out of adjustment the two beams strike the surfaces 82 and 83 at different distances from the roof edge of the prism 77. One of these beams is reflected by the surface 82 through the other surface which is semi-transparent and thence to the reflecting surface 85 on a prism cemented to the main dihedral reflector, and in turn through the comparison plane 69 to the eyepiece 70. The other element beam passes through the surface 83 and is reflected by a reflector 84, in the comparison plane in this embodiment, back to the surface 83 and thence to the reflector 85 and in turn to the eyepiece 70. When the instrument is out of adjustment the two images 78' as shown in Figs. 4A and 5A are out of coincidence. These may be brought into coincidence by adjustment of a light deviator 81. As long as the instrument is in adjustment as indicated by coincidence of the images 78', the range may be read directly by adjusting a light deviator 80 which operates on only one of the object beams and not on the element beam, the calibration being correct when the images 78' are in coincidence.

The arrangement shown in Fig. 8 has the disadvantage that the light paths for the two parts of the adjustment coincident element are slightly

different. In Fig. 9 this is overcome by the addition of another rhomb 86 so that both the lower and the upper parts of the line 73 send light through a rhomb.

It will be noted that when the instrument is in proper adjustment, the images of the adjustment coincident element are coming to focus approximately in the comparison plane 69, or after reflection halfway between the surfaces 82 and 83. Since the eyepiece 70 is focused on the plane 69, the additional path between this surface, as reflected by the surface 85, causes the images to appear slightly blurred. In Fig. 6 this is overcome first by moving the whole prism assembly 10 back of the eyepiece focal plane 91 so that the object images are exactly between the surfaces 82 and 83 as shown by the point 93, and second by the addition of a negative lens 94 to compensate for the difference in distance of the comparison plane 91 and the image 93. Actually this lens 94 is very small in diameter compared to the eyepiece 70 since it has to cover only a small part of the field. In fact this Fig. 6 shows that the roof edge of the dihedral reflector is usually not exactly in the focal plane.

However, this arrangement shown in Fig. 6 is not as convenient as that shown for a similar purpose in Fig. 7. In Fig. 7 the prism 77 is replaced by a thick one 95, whose front face 96 is optically, after reflection at the various surfaces, at a distance from the plane 91 equal to the actual distance of this surface 96 from the comparison plane 91. That is, in the absence of any prism assembly the element images, as shown by the broken lines 92, would be formed in the comparison plane 91. However, due to the thickness of the glass and the reflection at the various surfaces, these images are formed at the points 97 which are also in the comparison plane 91 and hence in focus through the eyepieces of the instrument. Figs. 7 and 7A also show another preferred feature of the invention in which the total reflecting surface 98 covers only a horizontal strip, the rest of the area being preferably painted black. With this arrangement the two parts of the element images 99 and 100 are perfectly complementary to one another even though both of the original parts of the element are continuous. The arrangement shown in Fig. 4 has the disadvantage that the instrument has to be in perfect vertical adjustment in order for the complementary features of the element to carry around to and appear in the element images 78'. In Figs. 7 and 7A, however, the complementary feature is not introduced until at the images themselves and therefore is not so sensitive to adjustment of the instrument.

In Figs. 10, 10A and 11 only part of a range finder system is shown since the remainder of it may be identical to that shown in Fig. 1. Light from a lamp 105 illuminates a vertical slit 106, the term vertical being used purely in the optical sense. A relay lens 107 forms an image 111 of this slit on an interface of a prism assembly, one-half 109 of which interface is fully reflecting. The light passes through a semi-transparent surface 108 of this prism and the upper half passes over the reflector 109 and is reflected from surface 110 to form part of the adjustment coincident element. The other half is reflected by the surface 109 and the semi-transparent surface 108 to form the other half of the element. At the receiving end of the element light beam a similar prism assembly forms a single image 111, after reflection at the roof surfaces 115 and

116 of a porro prism. The lower half 117 of the interface receiving the image 111', is silvered and through the surface 116 which is semi-transparent, the image 111' may be viewed by the eye 118 of an observer. As the instrument gets out of adjustment, the image splits up forming two parts 119 as shown by broken lines in Fig. 10A. The operation is of course the same as for Figure 1.

In Figs. 12 and 13 a coincidence range finder, or at least part thereof since the remainder is identical to Fig. 4, is shown in which light from a lamp 125 illuminates a slit 126 which is imaged by a lens 127 in the central plane of a prism system 128 as a bright line of light 149. The lower half 134 of this interface is silvered to reflect the light back to a semi-transparent interface 132 between two prisms 131 and 133 forming part of the prism assembly 128. The upper half of the interface transmits the light to another semi-transparent surface 136 between prisms 135 and 137 also constituting part of the prism assembly. These two beams then reflected by the surfaces 132 and 136 pass forward and are reflected by the prism 68 around the range finder optical system, from one viewing point to the other and back to prism 67 and thence into focus toward the comparison plane 69. The same prism assembly 128 now acts to receive both of these beams and to reflect them toward one another forming images 140' in the interface, the part of the image 140' reflected from the surface 132 passes over the reflecting surface 134 whereas the other part as reflected by the surface 136 strikes the mirror 134 and both of them pass to the eyepiece 129 and thence to the eye 130 of an auxiliary observer.

Fig. 14 shows a slightly different arrangement permitting the auxiliary observer to be on the same side of the comparison plane 69 as the range correction setting mark 126. In this case the central prism interface is made of four parts, the center two, 141, of which are reflecting so that the images 140' are directed to the eyepiece 142 and thence to the eye 143 of the auxiliary observer.

Figs. 15 to 18 show an alternative arrangement for providing the two vertical lines or marks. A lamp 150 illuminates a transverse slit 151 positioned optically above the comparison field. This slit 151 is imaged by a lens 152 and a dihedral reflector 153 with its roof surfaces 154 positioned optically above the comparison field. This slit 151 is imaged by a lens 152 and a dihedral reflector 153 with its roof surfaces 154 positioned optically above the comparison field. This provides two horizontally spaced vertical lines (actually virtual images of a line) in the comparison plane, without the use of any semi-transparent reflector.

Fig. 19 shows a prism assembly in which reflecting surfaces 163 and 164 correspond to the dihedral reflectors 153 and 154 respectively.

In the arrangement shown in Fig. 20 a similar pair of dihedral reflectors is used so that light from a lamp 155 illuminates a slit 160 which is imaged by a pair of lenses 161 and 162 on the dihedral reflector 153. The optical system includes a semi-transparent mirror 163 so that the same pair of dihedral reflectors can be used to receive the returning beams and to direct them upwards through the semi-transparent reflectors 163 and a lens 164 to the eye 165 of an auxiliary observer.

In Fig. 21 the semi-transparent reflector 163 is eliminated by having the mark producing optical system on one side of the comparison plane 69 and by having a viewing system symmetrically located at the other side and consisting of a dihedral reflector 168 to receive the beams from the reflectors 154 and to direct them through an eyepiece 169 to the eye 170 of an auxiliary observer.

Figs. 22 and 22A illustrate a form of the invention in which an incoming pair of rays 176 from the two parts of the range correcting setting mark strike the two roof surfaces 179 and 180 of a dihedral reflector having its roof edge in the comparison plane 175. The surface 180 is below one ray so that it passes straight through and is reflected by a mirror 177 in the comparison plane 175. Both rays after reflection are again reflected by a semi-transparent mirror 178 to an eyepiece 181. As long as the instrument is out of adjustment the rays 176 strike the roof surfaces 179 and 180 at different distances from the roof edge as shown, but if the instrument is adjusted properly these rays are at the same distance from the roof edge (which is conjugate to a line midway between the two vertical lines constituting the mark) and both rays striking the eyepiece 181 are in coincidence.

In Figs. 23 and 23A exactly the same set-up is used with a single beam 185 (with upper and lower halves) arriving to strike the surface 180 part of it to pass over it and the other part to be reflected to the surface 179. As long as the instrument is out of adjustment the eye sees two images as shown and when the instrument is in adjustment the ray 185 strikes the roof edge at the line of intersection 179 and 180 and hence only a single image is then seen. Thus, the invention is broadly operable with but a single mark sending light around the system, but such an arrangement has a very definite disadvantage in practice because at exactly correct setting, the setting system utilizes the roof edge of a dihedral reflector and hence this edge is more critical than is convenient to manufacture. The arrangement shown in Figs. 23 and 23A is only one of many arrangements using a single line but the trouble at the roof edge occurs with all of them.

Fig. 24 is included to show the advantage of having a dihedral reflector with its roof edge in the comparison plane. If the reflector surfaces 179 and 180 are tipped so as to rotate about the roof edge to the position shown by broken lines 186 and 187, it is noted that the rays shown by broken line 188, still come into coincidence if they were in coincidence before the dihedral reflector was tipped. For this reason all preferred embodiments of the invention have the roof edge of the dihedral reflectors in the final comparison plane.

Having thus described various embodiments of our invention and the manner in which it is applicable to stereo range finders and to coincidence range finders, we wish to point out that it is not limited to these specific structures but is of the scope of the appended claims.

What we claim and desire to secure by Letters Patent of the United States is:

1. A range finder of the type having two horizontally spaced viewing points at which light beams are received from the object being ranged, an optical system for directing and focusing the light beams to form images in comparison planes, means for viewing the images and light devia-

ting means for adjusting one of the object images relative to the other, said range finder being characterized by an adjustment coincident element at least optically in one of the comparison planes, means for projecting through at least the optical equivalent of said optical system, light from said element into focus forming two images, each an image of part of said element, near the other plane, opposed reflector means approximately at said other plane for converting horizontal movement of both images into a relative movement thereof twice that of either image alone.

2. A range finder according to claim 1 in which the adjustment coincident element consists of both a scale and an index for the scale, the image of the index moving along the image of the scale as the light deviating means is adjusted.

3. A range finder according to claim 1 in which the adjustment coincident element consists of two vertical lines corresponding to the two images, said lines being at least optically horizontally spaced in said one of the comparison planes.

4. A range finder according to claim 1 in which the adjustment coincident element consists of two vertical lines corresponding to the two images, said lines being at least optically horizontally spaced in said one of the comparison planes, and the opposed reflector means includes a dihedral reflector with its roof edge vertical and in said other plane.

5. A range finder according to claim 1 in which the opposed reflector means includes a dihedral reflector with its roof edge vertical and in said other plane.

6. A range finder according to claim 1 in which the opposed reflector means includes a porro prism with its roof edge vertical and in said other plane at the point which is conjugate to the optical middle of the element when the range finder is in proper adjustment.

7. A range finder of the type having two horizontally spaced viewing points at which light beams are received from the object being ranged, an optical system for directing and focusing the light beams to form images in comparison planes, means for viewing the images and light deviating means for adjusting one of the object images relative to the other, said range finder being characterized by an adjustment coincident element consisting of two vertical lines, at least optically horizontally spaced in one of the comparison planes, means for projecting through at least the optical equivalent of said optical system, light from both lines into focus forming two line images near the other plane, a dihedral reflector with its roof edge approximately in the other plane at the point which is conjugate to one optically halfway between the two lines when the range finder is in proper adjustment and means for viewing the two line images.

8. A range finder according to claim 7 in which said element includes a single illuminated ver-

tical mark and a beam splitter in front of the mark forming at least one of said lines as a virtual image of said mark.

9. A range finder according to claim 7 in which said lines are virtual images of a mark formed by a beam splitter near said one of the planes.

10. A range finder according to claim 7 in which the dihedral reflector is a porro prism and the latter viewing means includes at least one additional reflector.

11. A range finder according to claim 7 in which the dihedral reflector is right angled and receives light from the images respectively on its two roof surfaces.

15 12. A range finder according to claim 7 in which the dihedral reflector is right angled and at least one additional reflector is included between the dihedral roof surfaces for reflecting the light from the lines sideways and into alignment.

20 13. A range finder according to claim 7 in which the dihedral reflector is right angled with one roof surface semi-transparent and in which in said other plane behind at least part of said semi-transparent surface there is a plane reflector for reflecting light transmitted by said surface back to the semi-transparent surface which also receives light from the other roof surface and directs these two beams of light into alignment.

25 30 14. A range finder according to claim 7 in which the dihedral reflector includes a thick porro prism with another right angled prism cemented to one roof surface of the porro, the interface being semi-reflecting, at least part of the hypotenuse face of the other right angled prism behind the interface being reflecting and the line image viewing means including the other roof face of said other prism for directing to the object 35 40 image viewing means, light beams transmitted and reflected from the interface.

45 15. A range finder according to claim 7 in which the dihedral reflector includes a thick porro prism with another right angled prism cemented to one roof surface of the porro, the interface being semi-reflecting, at least part of the hypotenuse face of the other right angled prism behind the interface being reflecting and the line image viewing means including the other 50 55 roof face of said other prism for directing to the object image viewing means, light beams transmitted and reflected from the interface, the thickness of the porro prism from entrance face to roof edge plus the length of the hypotenuse face of said other prism, all divided by the index of refraction of the prisms being approximately equal to said porro prism thickness whereby said line images will be approximately on said hypotenuse face and in focus in the object image viewing means.
